UNITED STATES PATENT OFFICE.

JULIUS KINDEVATER, OF RICHMOND, VIRGINIA, ASSIGNOR, BY DIRECT AND MESNE ASSIGNMENTS, TO LOCOMOTIVE SUPERHEATER COMPANY, OF NEW YORK, N. Y., A CORPORATION OF DELAWARE.

STEAM-BOILER SUPERHEATER.

1,165,977.

Specification of Letters Patent. Patented Dec. 28, 1915.

Application filed March 25, 1908, Serial No. 423,175. Renewed March 19, 1912. Serial No. 684,811.

To all whom it may concern:

Be it known that I, JULIUS KINDEVATER, a citizen of the United States, residing at Richmond, in the county of Henrico and State of Virginia, have invented certain new and useful Improvements in Steam-Boiler Superheaters, of which the following is a specification.

My invention relates to steam superheaters, and more particularly to locomotive steam superheaters of that type in which superheater tubes are arranged in the flues of the locomotive boiler and are connected with headers located in front of the tube sheet in which the flues are set. In devices of this class, as is well known, the saturated steam header is connected with the dry pipe of the boiler, and the superheated steam header is connected to the steam chests of the locomotive engines. The steam from the dry pipe passes from the saturate steam header through all of the superheater elements into the superheated steam header, whence it flows to the cylinders. Heretofore, a great objection to such superheaters has been the difficulty of arranging the elements in such a manner that ready access may be had to any of them for inspection or repairs. In many of the well known types, it is necessary to dismantle practically the entire structure in order to remove or replace a single tube.

The primary object of my invention is, therefore, to provide a construction in which any superheater tube or element may be quickly removed, independent of any other.

A further object of the invention is to so arrange the parts that ready access may be had at all times, not only to the superheater elements for inspection or repair, but also to all the associated flues, for cleaning the same.

A further object of the invention is to simplify the means for securing the tubes to the headers, and to so arrange the parts that the least possible number of bolts is required to hold the tubes in position.

A further object of the invention is to provide an improved construction of damper for controlling the draft through the flues employed for superheating.

With the above and other objects in view,

and to improve generally upon the structural details of such devices, my invention 55 consists in the construction and arrangement of parts hereinafter described, and illustrated in the accompanying drawings, in which:—

Figure 1 is front elevation of my complete 60 superheater, the same being shown as in position in the boiler, and parts being broken away. Fig. 2 is a longitudinal vertical section thereof substantially on the line 2—2 of Fig. 1, parts being broken away. Fig. 65 3 is a longitudinal horizontal section, substantially on the line 3—3 of Fig. 1. Fig. 4 is a fragmentary sectional plan showing the damper and associated parts. Fig. 5 is an enlarged detail view of some of the 70 parts shown in Fig. 3. Fig. 6 is a side elevation of a part hereinafter described. Fig. 7 is a fragmentary vertical section through the steam headers. Fig. 8 is a fragmentary view similar to Fig. 2, but showing a slightly modified arrangement. Fig. 75 9 is an enlarged plan view of a modified form of one of the parts hereinafter described. Fig. 10 is a transverse section thereof on the line 10—10, and showing, in 80 addition, a fragment of one of the superheater tubes or elements. Fig. 11 is a fragmentary side elevation showing an arrangement for controlling the damper.

Referring to the drawings in detail, 1 85 represents the boiler shell, and 2 the usual dry pipe, provided with a fitting, 3, where it passes through the tube-sheet 4. The ordinary fire tubes are designated by the numeral 6, and, as is customary in such apparatus, additional large flues 5, are provided, in which are located the superheater elements or tubes 7. As clearly shown in Fig. 1, I arrange these large flues in a plurality of vertical rows, and preferably group these 90 rows in pairs, the distance between the members of any pair, and the distance between the pairs, being different. All the rows may, however, be equally spaced if desired.

The saturate steam header comprises a 100 body portion, 8, having a flange, 8', connecting with the end of the dry pipe, and a plurality of branches, 9, which may be either integral with the body of the header or bolted thereto. The body portion 8 extends 105 substantially horizontally, and is disposed

above the flues 5, while the branches 9, project from the bottom of said body portion substantially at right angles thereto, and extend downwardly between the flues of 5 each pair of vertical rows.

The superheated steam header is the counterpart of the saturate header, but is reversely arranged. As shown in Figs. 1 and 2, it comprises the horizontally extending body portion 10, and the upwardly projecting branches 11. It will be particularly noted that the branches 11 are similar to and correspond exactly with the branches 9, and further that these branches 9 and 11, are not staggered, but disposed in perfect alinement, one behind the other. This arrangement provides a large free space between the pairs of branches for inserting and removing the superheated tubes, as hereinafter described, and also admits of ready access being had to the large flues for inspection, cleaning, or repairs. Flanged couplings, 24, project from the front of the body of the superheated steam header, 10, and from these extend suitable pipes (not shown) to the steam chests of the engines.

As clearly shown in Fig. 7, the two headers comprise but a single casting, the respective and corresponding branches being united by integral webs 22. Air spaces 21, are, however, preserved between the branches of the two headers, in order that one may be insulated from the other as much as possible to avoid the cooling of the superheated steam by saturate steam, and in order that the hot gases and products of combustion may circulate freely between the headers.

In order to facilitate the ready detaching of any superheater tube from the headers, I employ the novel construction illustrated in detail in Fig. 5. By reference to this figure, it will be seen that I provide anchor blocks, 12, into which the ends of a pair of tubes are secured preferably by expanding and beading as indicated at 17. Bosses 16 are formed on the anchor blocks, and the sides of the branches 9 and 11 are provided with seats, 19, to receive these bosses. Packing rings 18, of asbestos, or other suitable material are preferably interposed between the beaded ends of the tubes and the seats, 19. Yokes, 13, are arranged so as to bridge two anchor blocks 12, and are provided centrally with openings through which pass the ends of bolts 14. As clearly shown in Fig. 5 each of these bolts has a square portion at its middle which lies within the space 21 between two branches, and is provided with threads and nuts 20, at each end. A single bolt, therefore, serves to secure in position against the headers the tubes on both sides of any pair of branches. With the single return construction illustrated in Fig. 2, it is evident that one bolt serves to hold all the tubes in a pair of large flues. As shown in

Fig. 8, however, I may employ the double return arrangement, and in this case it will be seen that the single bolt takes care of all the tubes in two pairs of flues. In either of the above constructions, it will be understood that the tubes of each pair are connected at their rear ends by U-shaped couplings, 23, as is usual.

In Fig. 3, most of the tubes shown are of the single return type, but at the extreme left of this figure I have illustrated a double return tube, 40, having the bend 41, similar to that shown in Fig. 8.

Instead of the anchor blocks 12, and yokes 13, illustrated in the first eight figures of the drawing, I may employ the construction shown in Figs. 9 and 10. In this arrangement, I dispense with the yokes, altogether, and use an anchor plate 42, having four tube openings 46, instead of two, and provided with strengthening ribs, 47. It is also formed with a central opening for the reception of the bolt 14. Also in these figures, I have illustrated the use of a gasket, 45, of soft copper or the like, in place of the asbestos packing above referred to. In this case the ends of the tubes are faced to receive the gasket.

It is evident that either type of anchor plate above described may be employed with either the single or double return tube construction, and that this use of the single clamping bolt for a plurality of tubes greatly lessens the labor of removing or detaching any tube or set of tubes. Furthermore, the arrangement of header branches between the alternate rows of flues as described, and the connection of all tubes to the sides of these branches, renders possible the ready removal of any tube or set of tubes desired, without in the least disturbing any other tube or its connections. This is a feature of great practical importance.

In superheaters of this character it is necessary to provide some means for controlling the flow of gases through the flues in order to prevent the burning of the superheater tubes when no steam is passing through them. To this end I provide a casing 25 arranged in front of the headers, and secured to the boiler shell as by brackets 26. At its lower edge the casing is secured to the upper part of the header 10 as at 27, and also extends down over the front face of this header till it abuts at its ends against plates 29, one at each side of header 10, supported by brackets 29^a attached to the boiler shell. These plates 29 help to form the bottom of the inclosure of which casing 25 is the front wall, and angle irons 28, on either side of the header, serve to secure the two parts together.

Lying in the same plane as the plate 29, and co-operating therewith to form the bottom of the inclosure, is a pivoted damper, 30, secured to a shaft 32 which extends trans-

versely of the boiler shell. When in its closed position, as shown in full lines in Fig. 2, the damper abuts at one edge against a flange 31 formed on the header 10, and at its 5 other edge, against brackets 33, supported by the tube sheet 4, and boiler shell. A crank 34 is secured to the shaft 32 at one end outside the boiler, and this in turn is connected by means of a link with the piston rod 35 of a 10 small cylinder 36. This cylinder is suitably connected by means of a pipe with the main engine cylinder in such manner that when steam is admitted to the main cylinders it flows also to cylinder 36, causing the piston 15 to move the damper to its open position, shown in dotted lines in Fig. 2. When, however, the throttle is closed, and steam is shut off from the engine, a spring or counter-weight serves to throw the damper to its 20 closed position, and thus entirely interrupt the passage of the products of combustion through the superheating flues.

In the construction shown, a crank lever 34^a is mounted outside the boiler shell on 25 the extended end of the shaft 32, and a coil spring 35^a has one end attached to the end of this lever, and the other end anchored to a bracket 36^a, secured to the shell. Other arrangements may, however, be employed.

30 In order to render the headers and superheater elements easily accessible, a series of openings are formed in the casing 25 opposite the flues, 5. These openings are normally closed by means of removable plates 37, held in position by clamps 38. By removing any desired plate access may be had to the corresponding part of the superheater structure.

It will thus be seen that I have provided a 40 very simple, convenient, and practical construction of superheater, and it is thought the numerous advantages of my invention will be readily appreciated by those skilled in the art.

45 What I claim is:—

1. In a superheater for locomotive boilers, a saturate steam header, a superheated steam header, each of said headers comprising a body portion and a plurality of 50 branches extending therefrom, said body portions being separated by a distance approximately equal to the length of said branches, the corresponding branches of said headers being disposed one directly behind the other in substantial alinement, and superheater tubes communicating with the sides of the said branches.

2. In a superheater for locomotive boilers, superheated and saturate steam headers, 60 each of said headers comprising a body portion and a plurality of branches extending substantially at right angles thereto, the corresponding branches of the two headers being secured together and disposed one behind the other in substantial alinement, but

spaced apart and said body portions lying at opposite ends of said alined branches, and superheater tubes communicating with the respective branches.

3. In a superheater for locomotive boilers, superheated and saturate steam headers, 70 each comprising a horizontally extending body portion and substantially vertically extending branches, projecting therefrom, the corresponding branches of said headers being disposed one behind the other in substantial alinement, said headers being formed integral with each other, but separated by an air space, and the said body portions lying at opposite ends of the vertical 75 alined branches.

4. In combination with a locomotive boiler, a plurality of vertical rows of large flues extending therethrough, saturate and superheated steam headers comprising oppositely disposed body portions having longitudinally alined branches extending therefrom in front of said flues between the vertical rows thereof, and superheater tubes located in said flues and having their ends 80 secured to the sides of said branches.

5. In combination with a locomotive boiler, a plurality of vertical rows of large flues extending therethrough, a saturate steam header comprising a horizontal body 95 portion disposed above said flues and provided with downwardly extending branches projecting in front of said flues and between the vertical rows thereof, a superheated steam header comprising a horizontal body 100 portion disposed below said flues, and provided with upwardly extending branches corresponding with said first named branches, the branches of one header being disposed directly behind the corresponding 105 branches of the other, and superheating tubes located in said flues and communicating with said respective branches.

6. In combination with a locomotive boiler, a plurality of rows of flues, saturate 110 and superheated steam headers disposed one behind the other in front of said flues in substantial alinement and extending between the rows thereof, superheater tubes disposed within said flues and having their 115 ends set into anchor blocks, and means for securing said anchor blocks against the sides of said headers, said means comprising a yoke spanning two adjacent blocks and a single bolt passing between said headers 120 through said yoke and serving to maintain two pairs of tubes in position on each side of said headers.

7. In a superheater for locomotive boilers, saturate and superheated steam headers 125 having branches arranged one behind the other in substantial alinement and spaced slightly apart, superheater tubes disposed on each side of said branches and having their ends secured in anchor blocks, seats 130

formed in the sides of said branches to receive said anchor blocks, yokes spanning adjacent pairs of blocks on each side of a branch, and double ended bolts passing through said yokes having rectangular middle portions lying in the space between two branches and serving to hold the anchor blocks on each side against their seats.

8. In a superheater for locomotive boilers, 10 saturate and superheated steam headers having branches arranged one behind the other in substantial alinement, and spaced slightly apart, superheater tubes having their ends set into anchor blocks, seats formed in said 15 branches to receive said anchor blocks, a yoke bridging two adjacent blocks, and a bolt passing through said yoke and serving to maintain both anchor blocks in position.

9. In a superheater for locomotive boilers, 20 saturate and superheated steam headers having branches arranged in substantial alinement and spaced slightly apart, superheater tubes disposed on each side of said branches and having their ends set into anchor blocks, seats formed in opposite sides of said branches to receive said anchor blocks, yokes bridging two adjacent blocks on each side, and a bolt passing through a pair of opposing yokes and serving to secure both pairs of anchor blocks in position.

10. In combination with a locomotive boiler, a plurality of vertical rows of flues extending therethrough, said rows being disposed in pairs, the members of each pair being spaced farther apart than the members of one pair from those of another, and a steam header, having a substantially horizontal body portion, and branches extending therefrom and projecting between the 40 members of each pair of vertical rows of flues.

11. In combination with a locomotive boiler, a plurality of vertical rows of large flues extending therethrough, a steam header 45 having a substantially horizontal body portion, and a plurality of branches extending therefrom and projecting between alternate vertical rows of flues, a second steam header having branches arranged behind those of 50 the first in substantial alinement, and superheater tubes disposed within said flues and connected with each side of each of said branches.

12. In combination with a locomotive 55 boiler, a plurality of flues extending therethrough and terminating in the usual tube sheet, superheater tubes arranged within said flues, steam headers, to which said tubes are connected disposed in front of said 60 tube sheet, one of said headers comprising a horizontally extending body, a casing comprising a front wall extending from the front face of said body to the boiler shell, and inclosing said headers, and a floor to 65 said casing extending from said body to the

tube sheet, a section of said floor being movable and constituting a damper for controlling the draft through said flues.

13. In combination with a locomotive boiler, a plurality of flues extending therethrough and terminating in the usual tube sheet, superheater tubes arranged within said flues, steamheaders with which said tubes connect, disposed in front of said sheet, a casing inclosing said headers, said casing 75 being provided with openings through which access may be had to said tubes, and removable plates normally closing said openings.

14. In a superheater for locomotive boilers, the combination with a steam header member located in the smoke box, and superheating tubes adapted to be connected to said header member, of means for attaching said tubes to said header member, such 80 means comprising anchor blocks into which one or more tube ends are permanently secured, seats in said header member adapted to receive said anchor blocks, a yoke bridging two adjacent blocks, and a bolt passing 85 through said yoke and serving to maintain the parts in position.

15. In a superheater for locomotive boilers, the combination with a header structure, and superheater tubes adapted to be connected therewith and having enlarged ends, 90 of means for attaching said tubes to said header structure, such means comprising anchor blocks having openings in which such enlarged ends of the tubes are seated, and a yoke bridging two adjacent blocks, and a bolt passing 95 through said yoke and serving to maintain the parts in position.

16. In a superheater for locomotive boilers, a saturate steam header, a superheated steam header, each of said headers comprising a body portion and a plurality of parallel branches communicating therewith, said body portions being separated by a distance approximately equal to the 100 length of said branches, and lying at opposite ends thereof, all of said branches being rigidly united to the body portions of both headers, said branches being separated from each other by open air spaces, and seats 110 formed on said branches adapted to receive the ends of superheater tubes.

17. In a steam superheater, a saturate steam header, a superheated steam header, each of said headers comprising a body portion and a plurality of parallel branches communicating therewith, each branch of each header being secured directly to both headers, thereby uniting said headers into a rigid structure, said branches extending between said body portions, and each being separated from the other by an open air space, and seats formed on said branches adapted to receive the ends of superheater 125 tubes.

18. In a steam superheater, a saturate steam header, a superheated steam header, each of said headers comprising a body portion and a plurality of branches communicating therewith, each branch of each header being secured to both headers, thereby uniting said headers into a rigid structure, said branches extending between said body portions substantially at right angles thereto, and being disposed in parallel spaced relation with open slots between the same, and seats formed on said branches adapted to receive the ends of superheater tubes. 75
19. In a steam superheater, a saturate steam header, a superheated steam header, each of said headers comprising a body portion and a plurality of branches communicating therewith, said body portions lying substantially parallel with each other, each branch of each header being formed integral with both headers, thereby uniting said headers into a rigid structure, said branches extending between said body portions and being disposed in parallel spaced relation with open slots between the same, and seats formed in said branches adapted to receive the ends of superheater tubes. 80
20. In a steam superheater, a saturate steam header, a superheated steam header, each comprising a horizontally and transversely extending body portion, and a plurality of branches projecting therefrom substantially at right angles thereto, said branches extending between and rigidly connecting said body portions, and being disposed in spaced parallel relation with open slots between the same and adjacent branches communicating at opposite ends with the body portions of their respective headers. 85
21. In a steam superheater, a header structure comprising an integral casting of substantially rectangular shape, such casting comprising main saturate and superheated steam compartments located at opposite sides of the rectangle, and a plurality of branches extending between the same, and lying side by side in parallel relation, adjacent branches communicating at their opposite ends with their respective compartments, and a coupling forming an inlet to said saturate steam compartment and located centrally thereof, and a pair of couplings projecting from the face of said superheated steam compartment adjacent opposite ends thereof, and forming outlets. 90
22. In a superheater for locomotive boilers, the combination with the usual tube sheet, of saturate and superheated steam headers disposed in front of the same, each of said headers comprising a body portion and a plurality of branches communicating therewith, said body portions extending horizontally and substantially parallel with the tube sheet, and said branches extending 95
- between said body portions and being disposed in parallel spaced relation, each of said branches being substantially rectangular in cross-section, and having at least one face lying perpendicular to the tube sheet, and superheater tubes communicating with said branches, the ends of each tube being connected with the perpendicularly disposed faces of two adjacent branches, such faces lying in the same plane. 100
23. In a superheater for locomotive boilers, the combination with the usual tube sheet, of saturate and superheated steam headers disposed in front of the same, each of said headers comprising a body portion and a plurality of branches communicating therewith, said body portions extending horizontally and substantially parallel with the tube sheet, and said branches extending between said body portions at substantial right angles thereto, all of said branches and headers being rigidly and permanently connected to form a unitary structure, and said branches being disposed in parallel relation and separated by air spaces, superheater tubes having their ends communicating with the branches of the respective headers, and bolts passing through the said air spaces between the branches and serving to maintain the tubes in position. 105
24. In a superheater for locomotive boilers, the combination with the usual tube sheet and smoke box, of a saturate steam header comprising a body portion located adjacent the tube sheet in the upper part of the smoke box, and extending horizontally transversely thereof, and a plurality of branches communicating therewith, a superheated steam header also comprising a body portion extending horizontally and transversely of said smoke box, a plurality of branches communicating therewith, all of said branches and headers being rigidly and permanently connected to form a unitary structure, said branches extending between said body portions at substantial right angles thereto, and being disposed in spaced, parallel relation, and superheater tubes having their ends communicating with the branches of the respective headers. 110
25. In a superheater for locomotive boilers, the combination with the usual smoke box, of a horizontally arranged saturate steam header located in the upper part thereof, a plurality of branches depending vertically from said header, superheater tubes having one end connected with said branches, a superheated steam header disposed below the first header, and parallel therewith, a plurality of branches upstanding from said second header, the other ends of said superheater tubes being connected with said upstanding branches, all the branches of both headers being disposed in parallel spaced relation, and the branches 115
- 120
- 125
- 130

of one header being arranged directly behind those of the other, in substantial alinement, longitudinally of the smoke box.

26. In combination with a locomotive boiler, a plurality of enlarged flues extending therethrough and terminating in the usual tube sheet, superheater tubes arranged within said flues, a steam header structure to which said tubes are connected disposed 5 in front of said tube sheet, said header structure comprising a horizontally disposed portion extending parallel with said tube sheet, a casing for said header structure and associated parts comprising a substantially 10 vertical front wall in engagement with said header structure, and extending from thence upwardly and laterally to the boiler shell, and a floor extending from the bottom edge of said front wall backwardly to the tube 15 sheet, said floor being formed, in part, of a pivoted damper, means for normally maintaining said damper closed, and means for automatically opening said damper when steam is admitted to the engine cylinders.
25. 27. In combination with a locomotive boiler, enlarged flues extending therethrough, and terminating in the usual tube sheet, superheater tubes arranged within said flues, a steam header structure with 30 which said tubes connect, disposed in front of said sheet, and a casing inclosing said header structure and tube ends, and comprising a substantially vertical front wall extending from the top of said boiler shell 35 to a point below said enlarged flues, said front wall comprising detachably connected sections.
28. In combination with a locomotive boiler, enlarged flues extending therethrough, and terminating in the usual tube sheet, superheater tubes arranged within said flues, a steam header structure with 40 which said tubes connect disposed in front of said sheet, and having a portion thereof 45 extending horizontally and transversely of the boiler, and a casing inclosing said header structure and tube ends, and comprising a substantially vertical front wall extending from the top of said boiler shell to a point 50 below said enlarged flues, said front wall being made up of a plurality of sections, some of said sections being supported by the horizontally extending portion of the header structure and being detachably secured in 55 place by means of clips.
29. In a superheater for locomotive boilers, the combination with the usual tube sheet, of vertical rows of enlarged flues terminating in said sheet, saturate and superheated steam headers having straight, elongated, vertically extending portions disposed 60 in front of said tube sheet and parallel therewith and located between said vertical rows of enlarged flues, and superheater tubes arranged 65 in said flues, and having their ends

connected with the lateral side faces of such vertically extending portions of said headers.

30. In a superheater for locomotive boilers, the combination with the usual front tube sheet, of vertical rows of enlarged fire tubes set therein, a header structure mounted adjacent said tube sheet and comprising straight vertically extending saturate and superheated steam compartments, disposed one directly behind the other in substantial 70 alinement, said alined compartments being located between said rows of tubes, and being rigidly united, but spaced apart, and superheater tubes lying within said enlarged fire tubes, and having their ends connected with 75 the sides of the respective compartments.

31. The combination in a boiler having a smoke box and tubes, of a superheater having a header made in a single piece and consisting of a series of columns spaced apart 80 and connected to manifolds at the top and bottom, with superheating pipes arranged to extend into the tubes of the boiler, and a head at the outer end of each pipe, with means for attaching the heads to the header 85 within the space between the two columns.

32. The combination in a boiler having a smoke box and flue tubes, of a superheater having a header made in a single piece and located in the smoke box, and a series of 90 circulating pipes extending into the flue tubes, the header having through passages 95 in which the pipes are mounted so that the said pipes can be removed from the tubes of the boiler through the header.

33. The combination in a locomotive boiler having a tube sheet and horizontal flue tubes and also having a smoke box section, with a superheater having a header located within the smoke box in front of the sheet, and having through passages, circulating pipes extending into the flue tubes and having heads located in the through passages and connected laterally with the header, with means for coupling the heads of the circulating pipes to the header, said means being accessible through the passages in the header.

34. In a superheater for locomotive boilers, the combination with the usual tube sheet, and flues terminating in said sheet, of a superheater comprising saturate and superheated steam compartments, each of said compartments being in the form of a straight hollow column, said columns being 115 vertically disposed parallel with the tube sheet and with each other, and superheater tubes arranged within said flues and having their ends respectively connected with the lateral side faces of said vertically extending 120 columns.

35. In a superheater for locomotive boilers, the combination with the usual tube sheet, and flues terminating in said sheet, of a superheater comprising saturate and su- 130

perheated steam compartments, each of said compartments being in the form of a straight, hollow column, extending vertically in front of the tube sheet and parallel therewith, one of said columns being located directly behind the other, in substantial alinement, longitudinally of the boiler, and superheater tubes arranged within said flues and having their ends respectively connected with the said vertically extending columns.

36. In a superheater for locomotive boilers, the combination with the usual tube sheet, and flues terminating in said sheet, of a superheater comprising saturate and superheated steam compartments, each of said compartments being in the form of a straight, hollow column extending vertically in front of the tube sheet and parallel therewith, one of said columns being located directly behind the other, in substantial alinement, longitudinally of the boiler, and superheater tubes arranged within said flues and having their ends respectively connected with the lateral side faces of said vertically extending columns.

37. In a superheater for locomotive boilers, the combination with the usual tube sheet, and flues terminating in said sheet, of a superheater comprising saturate and superheated steam compartments, each of said compartments being in the form of a straight, hollow column extending vertically in front of the tube sheet and parallel therewith, one of said columns being located directly behind the other, in substantial alinement, longitudinally of the boiler, and superheater tubes arranged within said flues and having their ends respectively connected with the lateral flat side faces of said vertically extending columns, such faces lying in the same plane.

38. In a superheater for locomotive boilers, the combination with the usual smoke box, of a superheater comprising straight, elongated, vertically extending saturate and superheated steam compartments in the form of hollow columns, a pair of such columns being located on each side of the center of the smoke box, and the members of each pair being disposed one directly behind the other, in substantial alinement, longitudinally of the boiler, and superheater tubes having their ends respectively connected with the lateral side faces of each pair of such vertically extending columns.

39. In a superheater for locomotive boilers, the combination with the usual smoke box and tube sheet, and vertical rows of flues

terminating in said sheet, of a superheater comprising straight, elongated, vertically extending steam compartments, a pair of such compartments being located at each side of the center of the smoke box, and the members of each pair being disposed one directly behind the other, in front of said tube sheet, and between two vertically extending rows of flues, one member of each pair being connected with the dry pipe of the boiler, and the other member of each pair being adapted for connection with one of the engine cylinders, and superheater tubes arranged within said flues on each side of each pair of said vertically extending compartments, and having their ends respectively connected with the lateral side faces thereof.

40. In a superheater for locomotive boilers, the combination with the usual boiler shell and tube sheet, forming a smoke box, and flues terminating in said tube sheet, of a header structure located in said smoke box and lying wholly within said boiler shell, said structure comprising a comparatively thin, flat, vertically extending portion disposed edgewise on each side of the center of the smoke-box, and having a flat lateral face lying in a plane at right angles to the tube sheet, and superheater tubes arranged within said flues and having their ends connected with such lateral side faces of said header structure.

41. In a superheater for locomotive boilers, the combination with the usual dry pipe and tube sheet, and flues terminating in said sheet, of a superheater comprising saturate and superheated steam header members, each of said members being in the form of a straight, hollow column, said columns being vertically disposed, parallel with the tube sheet, and with each other, some of said columns being closed at the lower end and connected at the upper end with said dry pipe, and others of said columns being closed at their upper ends and adapted to have their lower ends connected with the engine cylinders, and superheater tubes arranged within said flues and having their ends respectively connected with the lateral side faces of said vertically extending columns.

In testimony whereof I affix my signature, in presence of two witnesses.

JULIUS KINDERVATER,

Witnesses:

H. C. RUEGER,
ISAAC HELD.
